Manuel Pernas, Bayonne, N.J., assignor to Maidenform, Inc., New York, N.Y., a corporation of New York
Filed Aug. 10, 1966, Ser. No. 571,556
3 Claims. (Cl. 128—540)

In girdle constructions, it is customary where the major body of the garment is of stretch material, to employ an insert leading from the waist at the front of the garment downwardly to an area above the base or bottom line of the garment. This insert is generally restricted against lateral stretch and lies over the abdominal area of the wearer. The object of the present invention is to improve on such girdle construction by controlling the stretch of the fabric at the opposite sides of such insert, in that the fabric constituting the girdle body outwardly of the insert is provided with a specially formed, relatively narrow curved inner ply, over which is layed and seamed a corresponding formed innermost ply—all confined to the front of the girdle, and extending from its waistline to the crotch when the invention is applied to a panty girdle, as in the embodiment illustrated herein. Thus from the said insert and at each side for a distance within the free-stretch body of the garment, the lateral stretch thereof has progressive resistance over the abdominal area to a controlled degree.

The invention will be described with reference to the embodiment of the invention illustrated in the drawings, in which:

FIGURE 1 is a perspective view looking toward the front of the girdle, arrows showing lines of stretch of the body fabric;

FIGURE 2 is a vertical section taken downwardly on the line 2—2, FIG. 1 and looking toward the inner front face of the garment;

FIGURE 3 is a vertical section on the line 3—3, FIG. 1, looking toward the inner rear face of the garment;

FIGURE 4 is a horizontal section taken on the line 4—4, FIG. 2;

FIGURE 5 is a horizontal section taken on the line 5—5, FIG. 3.

FIGURES 4 and 5 are fragmentary only.

Referring to the drawings, it will be seen that the invention is shown as applied to a panty girdle having a body fabric 1 with free stretch vertically and transversely and formed into two panty legs with a crotch at 2. In this embodiment, the body fabric is provided with a waistband indicated at 3 and of stretch material, the waist band being shown as narrow at the front half of the garment and substantially widening at the rear half of the garment as indicated at 3^x. Below the waist band at the rear of the girdle, is shown a two-way stretch insert 4, and this may be employed if desired.

At the front of the girdle, a V-shaped insert 5 extends from the waist line to the crotch 2, this insert being without lateral stretch, or highly resistant lateral stretch, and at the same time having vertical stretch.

Directly applied to the inner face of the body fabric are two strips of material having the same lines of stretch as the body material and seamed to the latter, one at each side of said insert and seamed thereto. The said stretch-strips are indicated in FIG. 2 at 6.

Overlying the strip 6 at each side of insert 5 is a strip

2

7, which extends outwardly of strip 6 and substantially covers the same at the inner front face of the garment. The inner edge of strip 6 is seamed to insert 5, and its outer edge is seamed to the body fabric 1, but as indicated in FIG. 2 by dash lines, strip 6 is preferably not seamed at its outer margin to the wider strip 7. The latter strip, 7, is seamed at its inner edge to insert 5 and at its outer edge to the body fabric.

At the rear of the girdle the seat area is reinforced inwardly thereof by two panels 8 of two-way stretch material, seamed at their outer edges to the body fabric and cross-stitched to each other, as shown in FIGURE 3.

Referring to the drawings, it will be seen that both of the strips 6 and 7 are curved inwardly from top and bottom outer edges to a transverse line somewhat above the crotch, their outer margins then extending inwardly in a straight line. Thus the resistance controlled thereby is reduced along the center line of the abdomen and thence increases below said line.

It will be understood that various modifications may be made in the form and arrangement of the elements shown in the embodiment illustrated. In said embodiment, the strip 6 rises above the overlying strip 7, the top of the latter strip terminating below the waist band, so that the control is of lesser degree for a short distance below the waist band, this arrangement being preferred.

Having described my invention, what I desire to protect is as follows:

1. In a girdle, a body fabric, the body fabric being formed with joined back and front areas having two-way stretch and being provided with a waist band, of a vertical stretch insert at the front of the girdle diverging downwardly from the waist band to the lower portion of said girdle, in combination with two inner strips of at least transverse stretch, each strip having an inner margin seamed to the body fabric at an outer margin of said insert, one strip overlying the second strip, and one strip extending outwardly of the other strip, both strips being seamed at their outer margins to the body fabric, said strip which extends outwardly beyond the other strip having its top edge substantially below said other strip, and the top edges of both strips lying in an inwardly and upwardly directed extended angle.

2. A girdle constructed in accordance with claim 1, in which each strip extends downwardly with its outer margin formed in an elongated curve terminating at about the lower end of the insert, said outer margin thence being directed inwardly.

3. A girdle constructed in accordance with claim 1, in which the two strips at each side of the insert lie contiguous the insert and each has an outer elongated curved edge merging at its top with an inwardly and upwardly directed inclined edge extension, and also merging at its base with a downwardly and inwardly directed inclined edge extension.
